DESIGN FOR A CIGARETTE HOLDER
FIGURINE

Harry Edwin Hughes, Long Beach, Calif.

Application October 4, 1946, Serial No. 133,749

Term of patent 7 years

(Cl. D85—2)

To all whom it may concern:

Be it known that I, Harry Edwin Hughes, a citizen of the United States, residing at Long Beach, in the county of Los Angeles and State of California, have invented a new, original, and ornamental Design for a Cigarette Holder Figurine, of which the following is a specification, reference being had to the accompanying drawing, forming a part thereof.

I claim:

The ornamental design for a cigarette holder figurine, as shown.

HARRY EDWIN HUGHES.
